UNITED STATES PATENT OFFICE.

LEWIS WOLF, OF McNABB, ILLINOIS.

CARBURETER.

1,120,352.

Specification of Letters Patent.

Patented Dec. 8, 1914.

Application filed August 23, 1913. Serial No. 786,259.

To all whom it may concern:

Be it known that I, LEWIS WOLF, a citizen of the United States, and a resident of the city of McNabb, county of Putnam, and 5 State of Illinois, have invented certain new and useful Improvements in Carbureters, of which the following is a specification.

My invention relates to improvements in carbureters and has for its object the provision of an improved construction of this character whereby the fuel charge for explosive engines is thoroughly mixed and gasified before entering the engine.

10 The invention consists in the combination and arrangement of parts hereinafter described and claimed.

15 The invention will be best understood by reference to the accompanying drawing forming a part of this specification and 20 which is a sectional view of a construction embodying my invention.

The preferred form of construction as 25 illustrated comprises a fuel supply pipe 13 which is provided with a valve 14 for controlling the passage of fuel therethrough, said fuel supply pipe communicating with a charge supply pipe 9 passing transversely through the ordinary exhaust pipe 3 of the 30 engine. Supply pipe 9 is provided with a fibrous non-combustible material 10 which is arranged both in the portion extending through pipe 3 and also for a considerable distance below pipe 3. Pipe 9 is provided with a valve 11 for controlling the passage 35 of air therethrough and also with a fuel priming cup 12 for heating the same when desired. Fuel supply pipe 13 is connected with pipe 9 and extended into the fibrous

material 10 as shown. By this arrangement it will be observed that both the air and fuel 40 are passed through heated fibrous material before passing to the engine so that a thorough mixture is obtained which has been heated to facilitate the explosion.

While I have illustrated and described the 45 preferred form of construction for carrying my invention into effect, this is capable of variation and modification without departing from the spirit of the invention. I, therefore, do not wish to be limited to the 50 precise details of construction set forth, but desire to avail myself of such variations and modifications as come within the scope of the appended claim.

Having described my invention what I 55 claim as new and desire to secure by Letters Patent is:

The combination with the exhaust pipe of an explosive engine, of a charge supply pipe 60 extending transversely through said exhaust pipe and connected with the engine; fibrous material in said charge supply pipe in the portion in said exhaust pipe and in the portions beyond said exhaust pipe; a fuel cup 65 on said fuel supply pipe around said fibrous material; and valved means for admitting air and fuel to said charge pipe before it passes through said exhaust pipe, substantially as described.

In testimony whereof I have signed my 70 name to this specification in the presence of two subscribing witnesses.

LEWIS WOLF.

Witnesses:

WILLIAM H. JOHNSTON,
CASPER LATIMER.
